UNITED STATES PATENT OFFICE.

HARRY L. MOTTER, OF YORK, PENNSYLVANIA.

PUZZLE.

SPECIFICATION forming part of Letters Patent No. 414,986, dated November 12, 1889.

Application filed July 11, 1889. Serial No. 317,115. (No model.)

To all whom it may concern:

Be it known that I, HARRY L. MOTTER, a citizen of the United States, residing at York, in the county of York and State of Pennsylvania, have invented certain new and useful Improvements in Puzzles, of which the following is a specification, reference being had therein to the accompanying drawings, in which—

10 Figure 1 represents a plan view of my improved toy or puzzle, and Fig. 2 a transverse sectional view taken on the line xx of Fig. 1.

The object of the invention is to furnish an interesting and amusing puzzle or toy, which 15 may be cheaply manufactured, as will presently appear.

The invention consists of certain novel features of construction, which will be fully hereinafter set forth, and particularly pointed out 20 in the claim appended.

In the drawings annexed, the letter A designates a disk provided with a smooth upper surface and mounted upon a central pivotal cone B, the apex of the cone resting in a suitable recess in the bottom of the disk, whereby 25 the said disk may be readily rotated and oscillated in any direction. Upon the face of the disk is erected and suitably secured an outer octagonal inclosure a , within which is 30 formed a main rectangular inclosure b , a space or alley-way c being left between the two inclosures. The inclosure b communicates with the alley-way c at its corners and at about 35 the middle of each of its four sides by means of openings d , as shown. The inclosure b is

divided or partitioned off into a number of small squares, (preferably thirty-six,) which communicate with each other by openings similar to the openings d , above described. The four center squares are painted or otherwise distinguished from each other with different colors. Placed loosely in the alley-way c are four balls e , colored to correspond with the colors of the four central squares.

The object is to so manipulate the disk that 45 the balls will be placed and kept upon their respective central squares—the black ball upon the black square, the blue ball upon the blue square, and so on—the openings or gateways between the inclosures enabling this to 50 be done.

Having thus fully described my invention, what I claim, and desire to secure by Letters Patent, is—

A plate or disk provided upon its face with 55 an octagonal inclosure a and an inner rectangular inclosure b , this inner rectangular inclosure having side and corner openings d and being partitioned off into smaller inter-communicating rectangles, as shown and de- 60 scribed, in combination with a suitable number of balls e and a suitable pivotal support, substantially as described.

In testimony whereof I affix my signature in presence of two witnesses.

HARRY L. MOTTER.
